UNITED STATES PATENT OFFICE.

JOSIAH H. SMITH, OF PHILADELPHIA, PENNSYLVANIA, ASSIGNOR TO WILLIAM H. TIGERMAN, OF PHILADELPHIA, PENNSYLVANIA.

SUSPENSION-RAILWAY.

Specification of Letters Patent.

Patented Apr. 27, 1915.

1,137,361.

Application filed August 19, 1914. Serial No. 857,477.

To all whom it may concern:

Be it known that I, JOSIAH H. SMITH, a citizen of the United States, residing at Philadelphia, in the county of Philadelphia and State of Pennsylvania, have invented 5 certain new and useful Improvements in Suspension-Railways, of which the following is a specification.

My invention relates to improvements in 10 suspension railways, the object of the invention being to provide a suspension railway which is especially adapted for use in subways.

A further object is to provide an improved 15 construction of track supporting girders having an improved connection with transverse girders, the latter and the connecting means being anchored in cement forming the top of the subway and the foundation of 20 the base of the street above, so that the parts are rigidly secured together and held against movement in any direction.

With these and other objects in view, the 25 invention consists in certain novel features of construction and combinations and arrangements of parts as will be more fully hereinafter described and pointed out in the claims.

In the accompanying drawings: Figure 1 30 is a view in longitudinal section illustrating my improvements. Fig. 2 is a view in transverse section on the line 2—2 of Fig. 1, a portion of the subway roof construction being broken away. Fig. 3 is an enlarged view 35 in section on the line 3—3 of Fig. 2, and Fig. 4 is a view in vertical section on the line 4—4 of Fig. 2.

1 represents an underground tunnel or subway having side walls 2, a bottom wall 40 3, and a top wall 4. The top wall 4 constitutes the supporting base of the street 5 above, and is ordinarily of cement. In this cement roof 4, transverse girders 6 are embedded. These girders 6 are ordinarily extremely heavy I-beams, and act as supports 45 for the wall 4, the cement being arched between the I-beams as shown at 7.

8 represents my improved longitudinal 50 girders which are composed of upper and lower angle bars 9 and 10 respectively secured together by cross diagonal struts 11 and vertical struts 15.

At the points of intersection with the transverse I-beams 6, the longitudinal girders 8 are connected by anchor plates 12. 55 These anchor plates 12 extend between the angle bars 9 and 10, and are riveted thereto. Above the bars 9, the plates 12 are recessed as shown at 13 to accommodate the base flanges of the I-beams 6, and said plates at 60 their upper ends incline toward the I-beams, and at their opposite edges are provided with angle bars 14. The angle bars 14, and the portion of the plates adjacent the I-beams 6, are embedded in the cement of wall 65 4, so that the plates are securely anchored in the wall. Furthermore, the walls of recesses 13 provide supports upon the lower base flanges of the I-beams 6, hence the longitudinal girders are supported rigidly 70 on the I-beams and require no additional support for suspending the cars in the subway.

In constructing new subways, the parts 75 will all be assembled before the cement wall 4 is set. In utilizing my improvements in subways already constructed, it is necessary to cut out the cement wall sufficiently for the accommodation of the plates 12 with their angle bar edges, and after the parts are connected, the cement is filled in, so that the parts become securely anchored. The crossed diagonal struts 11 are secured at 80 their ends to the plates 12, and the vertical struts 15 support laterally projecting cantilevers 16 to which I-beams 17 are connected and support rails 18.

19 represents the cars of a subway train suspended from brackets 20 having wheels 21 to run on the tracks 22 supported on I-beams 17.

Various slight changes might be made in the general form and arrangement of parts described without departing from my invention, and hence I do not limit myself to 95 the precise details set forth, but consider myself at liberty to make such changes and alterations as fairly fall within the spirit and scope of the appended claims.

Having thus described my invention, what 100 I claim as new and desire to secure by Letters Patent is:

1. The combination with a series of transverse beams embedded in cement, of a longi-

- tudinal girder located below and extending at right angles to the transverse beams, anchor plates secured to and forming parts of the girder, said anchor plates projecting above the girder embedded in the cement, and secured to opposite sides of the beams, substantially as described.
2. The combination with a series of transverse beams embedded in cement, of a longitudinal girder located below and extending at right angles to the transverse beams, anchor plates secured to and forming parts of the girder, said anchor plates projecting above the girder embedded in the cement, and secured to opposite sides of the beams, said anchor plates having angles at their edges embedded in the cement, substantially as described.
3. The combination with a series of transverse beams embedded in cement, of a longitudinal girder located below and extending at right angles to the transverse beams, anchor plates secured to and forming parts of the girder, said anchor plates projecting above the girder embedded in the cement, and secured to opposite sides of the beams, and said anchor plates recessed at their edges conforming in shape to the shape of the beams, substantially as described.
4. The combination with a series of transverse beams embedded in cement, of a longitudinal girder located below and extending at right angles to the transverse beams, anchor plates secured to and forming parts of the girder, said anchor plates projecting above the girder embedded in the cement, and secured to opposite sides of the beams, said anchor plates having angles at their edges embedded in the cement, and said anchor plates recessed at their edges conforming in shape to the shape of the beams, substantially as described.
5. In a subway, the combination with a roof construction consisting of transverse I-beams embedded in cement, of a longitudinal girder consisting of upper and lower parallel angle bars, anchor plates secured between both pairs of angle bars and projecting above the girder, said plates having recesses in their edges receiving the base flange of the I-beams, substantially as described.
6. In a subway, the combination with a roof construction consisting of transverse I-beams embedded in cement, of a longitudinal girder consisting of upper and lower parallel angle bars, anchor plates secured between both pairs of angle bars and projecting above the girder, said plates having recesses in their edges receiving the base flanges of the I-beams, and angle bars secured to the upper edges of the anchor plates and embedded in the cement at opposite sides of the I-beams, substantially as described.
7. The combination with transverse beams, of a longitudinal girder, anchor plates secured to the girder and supported on the I-beams, and a portion of said plates and the I-beams embedded in cement, laterally projecting cantalivers secured to the longitudinal girder, and a rail supported at the outer ends of the cantalivers, substantially as described.
8. In a subway, the combination with an upper wall consisting of a plurality of transversely positioned beams embedded in the wall, of a longitudinal girder, anchor plates constituting portions of the girder, projecting above the girder, and recessed at their edges to receive the beams and anchored in the wall, laterally projecting cantalivers secured to the longitudinal girder, and a rail supported at the outer ends of the cantalivers, substantially as described.
9. In a subway, the combination with a roof construction consisting of transverse I-beams embedded in cement, of a longitudinal girder, anchor plates constituting a part of the girder and projecting above the girder, said anchor plates partially embedded in the cement and recessed to receive the lower base flanges of the I-beams, laterally projecting cantalivers secured to the longitudinal girder, and a rail supported at the outer ends of the cantalivers, substantially as described.
10. In a subway, the combination with a roof construction consisting of transverse I-beams embedded in cement, of a longitudinal girder located below the I-beams, and recessed anchor plates secured to the longitudinal girder and located at opposite sides of the I-beams, said anchor plates having angle bars at their edges anchored in the cement at opposite sides of the I-beams, laterally projecting cantalivers secured to the longitudinal girder, and a rail supported at the outer ends of the cantalivers, substantially as described.
11. In a subway, the combination with a roof construction consisting of transverse I-beams embedded in cement, of a longitudinal girder consisting of upper and lower parallel angle bars, anchor plates secured between both pairs of angle bars and projecting above the girder, said plates having recesses in their edges receiving the base flanges of the I-beams, laterally projecting cantalivers secured to the longitudinal girder, and a rail supported at the outer ends of the cantalivers, substantially as described.
12. In a subway, the combination with a roof construction consisting of transverse I-beams embedded in cement, of a longitudinal girder consisting of upper and lower parallel angle bars, anchor plates secured between both pairs of angle bars and projecting above the girder, said plates hav-

ing recesses in their edges receiving the base flanges of the I-beams, angle bars secured to the upper edges of the anchor plates and embedded in the cement at opposite sides of 5 the I-beams, laterally projecting cantilevers secured to the longitudinal girder, and a rail supported at the outer ends of the cantilevers, substantially as described.

In testimony whereof I have signed my name to this specification in the presence of 10 two subscribing witnesses.

JOSIAH H. SMITH.
